UNITED STATES PATENT OFFICE.

JOHN E. WITTMAN, OF PORTLAND, OREGON.

SHAWL-COLLAR FOR GARMENTS.

1,326,704.

Specification of Letters Patent. Patented Dec. 30, 1919.

Application filed July 3, 1919. Serial No. 308,648.

To all whom it may concern:

Be it known that I, JOHN E. WITTMAN, a citizen of the United States, and a resident of Portland, county of Multnomah, State of Oregon, have invented a new and useful Improvement in Shawl-Collars for Garments, of which the following is a specification.

My invention relates to garments made with a shawl collar.

10 Heretofore the perfect shawl collar effect was obtained by ironing and stretching the material at the outer edge of the collar. Such work requires considerable skill, consumes considerable time and is costly. It 15 is therefore usually bestowed upon high priced garments only. And even such skilful tailoring has an element of uncertainty; that is, it lacks uniformity in the effect produced, because the tailor may stretch the 20 goods too much, and in so doing cause a poor fitting effect.

The object of my invention is to eliminate the necessity for skilful stretching and ironing as the factor for obtaining a well fitted 25 shawl-collar, and, instead, to bring about, and assure, the same result as the inevitable, mechanical effect due to the making of the collar of the combination of pieces of the shapes hereinafter described, and sewn together by an ordinary operator.

I attain my object by cutting the component pieces of the collar of the shapes, and uniting the same, as hereinafter described; thereby causing the material at 35 the outer edge of the collar to acquire a fullness along lines radiating from the center lines of the shoulders; and by so doing, causing a hollow or concavity at the shoulders, adapted to conform to the convexity of the 40 latter, and thus causing the collar to lie smoothly over the shoulders.

In the accompanying drawings, constituting a part of this specification,

Figure 1 shows an outside view of the upper part of a garment provided with a shawl collar the latter being lifted so as to illustrate the elements entering into construction of the under piece of the collar.

Fig. 2 is an inside view of the garment 50 and of the elements entering into the construction of the top piece of the collar.

Fig. 3 shows part of a pattern for cutting one side of the front of the garment, and illustrates the curve of the line on which the 55 neck opening is to be cut.

Fig. 4 shows the pattern for cutting one-

half of the under piece of the collar which is sewed to the neck line of the piece shown in Fig. 3.

The piece shown in Fig. 4 is also shown in broken outline in Fig. 3, and there placed in relative position for sewing in place.

In Fig. 5, the piece shown in Fig. 4 is shown as sewn in place to the neck of the front piece of the garment shown in Fig. 3; Fig. 5 therefore also illustrates the resulting fullness in the underpiece of the collar, which fullness is also illustrated in Fig. 1.

Fig. 6 illustrates a part of the pattern for cutting one-half of the top-piece of the collar, such top piece being an integral part of the inner facings of the front of the garment.

Fig. 7 illustrates the insert which must be placed at the inner edge of the middle part of the under-piece of the collars for producing the required fullness in the shoulder portions of the latter; the fullness so obtained being illustrated in Fig. 2.

Figs. 8 to 10 show respectively a front view, a side view; and a back view of a figure wearing a garment made with my improved shawl collar and illustrates the fitting effects obtained.

My collar is made of an under-piece shown as a whole in Fig. 1, and top-piece, shown as a whole in Fig. 2; the component elements of these pieces being cut in the particular shapes, and sewn together in the manner hereinafter described.

Referring to Fig. 1; *a* represents the back of the garment; *b* the two front pieces.

The latter are made with the usual arm holes *c*, and the neck-line *d*, is cut to a suitable curve. The under-piece *e* of the collar may be made of one or more pieces as convenient, with a view of economy. If made of two pieces as *e'*, they would be sewed together as illustrated in Fig. 1; the line of juncture coinciding with the middle of the back. Each end of the collar is cut to the shape shown in Fig. 4. It will be noted that the base line *f* of these ends describes an arc of a circle of much greater radius than the arc described by the neck-line *d*, and this is one of the essential points to be observed in making my improved collar.

In attaching the under-piece *e* to the neck line of the front pieces *b* of the body of the garment, the seam *t* is started at a point *e²* of the under piece and the point *d'* of the neck line *d*, and carried across to similar

points at the opposite end of the under piece. In consequence the base line *f* of the ends of the under-piece *e* becomes arranged as illustrated in Fig. 5, thereby producing, and causing a fullness of the material at *g* along lines radiating from points *h*, lying in the center lines of the shoulders.

The top-piece of the collar and integral portions of the facing of the front of the garment is cut to the pattern shown in Fig. 6, in which *i* represents a portion of the top-piece of the collar, and *j* a portion of the "facing" integral therewith. The top-piece of the collar, as shown in Fig. 6, has triangular pieces *k* cut out, the sides of the triangle being designated by *l*; and in such angular openings is sewn an elongate insert *l*, of the shape shown in Fig. 7, the ends *l'* thereof being cut at an oblique angle. The sewing of the insert *l* in the collar piece *i* is started at a point *m*, the ends of the collar-piece *i* being drawn outward, as shown by broken lines *i'* in Fig. 6, to accommodate the insertion of the insert *l*, as also illustrated by broken outlines in Fig. 6. In the latter figure, the broken line *n* represents the center line of the collar and back of the garment.

When the insert *l* has been sewn in place a fullness will be produced at *o*, at the outer edge of the collar by a spreading of the material along lines radiating from said points *m*, designating the vertices of the removed triangular pieces *k*. Such fullness also being located at the center lines of the shoulder, indicated by the broken lines *p* in Fig. 2.

The under piece of the collar is first attached to the body of the garment, and then the top piece.

When the collar is constructed as above described the effects illustrated in Figs. 8 to 10 inclusive, will have been produced. As will be observed in Fig. 10, the outer edge of the collar *q*, will be adapted to lie snugly on the back of the person and the shoulder portions *r* will also have the proper shape and fit. Furthermore the back of the collar *s* will have tailored fit, to the neck of the figure permitting the shirt collar to project above the coat collar, and giving a pleasing effect.

My invention relates particularly to mackinaw garments, because in the making of those garments, the manufacturer cannot afford to put in any time for tailoring effects in order to bring about a neat fit for the collar.

By my invention the collar effect produced is no longer left to the discretion of the operator with uncertain results, but uniform good results are obtained by any operator capable of sewing pieces of cloth properly together without being required to pay any attention to the shaping of the collar, since that is the inevitable mechanical

result of the described construction of my collar.

My collar construction effects economy in material use, since the pieces may be cut out with a minimum of waste.

The collar pieces of course, must be cut in size to correspond with that of the garment, as will be understood by any experienced cutter.

I claim:

1. In a garment of the character described, a body part, and a shawl collar, having a circular neck-opening stitched to the latter, said shawl-collar made of an inner collar-piece whose outer edge describes an arc and whose inner edge describes the adjacent arcs of intersecting circles of equal radii, but much greater than the radius of said neck-opening, and an outer-collar piece having small triangular sections cut away at its inner or neck edge, the altitudes of these triangular sections coinciding with the center lines of the shoulders of the garment, and said outer collar-piece having an elongate insert at its inner edge, said insert having oblique diverging ends, the converging sides of said triangular openings of said outer collar-piece being sewn to the upper edge of said insert, and the diverging sides of said triangular openings being sewn to the oblique ends of said insert, thereby causing a fullness at the outer edge of the collar on lines radiating from the center lines of, and forming concavities at the shoulders of the garment, substantially as described.

2. In a garment of the character described, a shawl collar made of a collar piece having small triangular sections cut away at its inner or neck edge, the altitudes of these triangular sections coinciding with the center lines of the shoulders of the garment, and an elongate insert sewn to said inner edge between said triangular openings, said insert having oblique diverging ends, the converging sides of said triangular openings being sewn to the upper edge of said insert, and the diverging sides of said triangular openings being sewn to the oblique ends of said insert, thereby causing a fullness at the outer edge of the collar on lines radiating from the vertices of said triangular openings; such fullness producing concavities for receiving the shoulders of the wearer, substantially as described.

3. In a garment of the character described, a shawl collar made of a collar-piece having small triangular sections cut away at its inner or neck edge, the altitudes of these triangular sections coinciding with the center lines of the shoulders of the garment; and an elongate insert sewn to said inner edge between said triangular openings, said insert having oblique diverging ends, the converging sides of said triangular openings

being sewn to the upper edge of said insert, and the diverging sides of said triangular openings being sewn to the oblique ends of said insert, thereby causing a fullness at the 5 outer edge of the collar on lines radiating from the vertices of said triangular openings; such fullness producing concavities for receiving the shoulders of the wearer, and a companion collar-piece conforming to 10 said outer collar-piece, and forming with the latter concavities at the shoulders of the garment, substantially as described.

4. In a garment of the character described, a body part, the edge of whose neck 15 opening substantially describes an arc, and a collar-piece as e , whose outer edge describes an arc and whose inner edge describes the adjacent arcs of intersecting circles of equal radii but much greater than the 20 radius of said neck opening, the inner edge of said collar-piece being sewn to the edge of said neck opening, thereby producing a fullness at the outer edge of the collar on lines 25

radiating from the center lines of the shoulders of the garment, and forming concavities 25 for receiving the shoulders of the wearer, substantially as described.

5. In a garment of the character described, a body part, the edge of whose neck opening substantially describes an arc, and 30 a collar-piece as e , whose outer edge describes an arc and whose inner edge describes the adjacent arcs of intersecting circles of equal radii but much greater than the radius of said neck opening, the inner edge 35 of said collar-piece being sewn to the edge of said neck opening, thereby producing a fullness at the outer edge of the collar on lines radiating from the center lines of the shoulders of the garment, and a companion 40 collar-piece conforming to said inner collar-piece and forming with the latter concavity at the shoulders of the garment substantially as described.

JOHN E. WITTMAN.
